(57) **CLAIM**

The ornamental design for a projectile-shaped trailer air tank, as shown and described.

DESCRIPTION

FIG. 1 is a top-rear perspective view of a projectile-shaped trailer air tank showing the new design;

FIG. 2 is a close-up top-rear perspective view of the projectile-shaped trailer air tank of FIG. 1;

FIG. 3 is a right elevation view of the projectile-shaped trailer air tank of FIG. 1;

FIG. 4 is a left elevation view of the projectile-shaped trailer air tank of FIG. 1;

FIG. 5 is a top plan view of the projectile-shaped trailer air tank of FIG. 1;

FIG. 6 is a bottom plan view of the projectile-shaped trailer air tank of FIG. 1;

FIG. 7 is a front elevation view of the projectile-shaped trailer air tank of FIG. 1; and,

FIG. 8 is a rear elevation view of the projectile-shaped trailer air tank of FIG. 1.

The claimed ornamental design is shown in FIGS. 1-2 embodied on an assembly that may be used, for example, as a tanker trailer. In an illustrative example, the claimed ornamental design may operate as an air tank. The broken lines shown in the drawings illustrate unclaimed portions of the claimed design and form no part of the claimed design.
